(57) **CLAIM**

We claim the ornamental design for a handle for cookware, as shown and described.

DESCRIPTION

FIG. 1 is a perspective view of a handle for cookware according to the new design;

FIG. 2 is a front view of the handle for cookware shown in FIG. 1, the rear view being a mirror image thereof;

FIG. 3 is a left side view of the handle for cookware shown in FIG. 1, the right side view being a mirror image thereof;

FIG. 4 is a top view of the handle for cookware shown in FIG. 1; and,

FIG. 5 is a bottom view of the handle for cookware shown in FIG. 1.
